DESIGN FOR A SCAFFOLD JACK OR THE LIKE

John L. Daily, Johnstown, Pa.

Application June 25, 1940, Serial No. 93,241

Term of patent 14 years

To all whom it may concern:

Be it known that I, John L. Daily, a citizen of the United States, residing at Johnstown, in the county of Cambria and State of Pennsylvania, have invented a new, original, and ornamental Design for a Scaffold Jack or the like, of which the following is a specification, reference being had to the accompanying drawing, forming part thereof.

Figure 1 is a top plan view of a scaffold jack or the like showing my new design.

Figure 2 is a front elevational view.

Figure 3 is a left hand end elevational view.

Figure 4 is a right hand end elevational view.

Figure 5 is a rear elevational view.

Figure 6 is a bottom plan view.

Figure 7 is a front perspective view.

Figure 8 is a transverse vertical sectional view taken through Figure 2 along the line 8—8.

Figure 9 is a fragmentary longitudinal sectional view taken through Figure 2 along the line 9—9.

I claim:

The ornamental design for a scaffold jack or the like, as shown.

JOHN L. DAILY.
